FIG. 3

UNITED STATES PATENT OFFICE

CLARENCE L. BENTLEY, OF SAN PEDRO, CALIFORNIA.

CANNING-MACHINE.

1,101,245.

Specification of Letters Patent. Patented June 23, 1914.

Application filed March 15, 1913. Serial No. 754,561.

To all whom it may concern:

Be it known that I, CLARENCE L. BENTLEY, a citizen of the United States, residing at San Pedro, in the county of Los Angeles and State of California, have invented a new and useful Improvement in Canning-Machines, of which the following is a specification.

This invention relates to canning machines, and the principal object is to provide a conveyer in which the material to be canned is placed and automatically conveyed to the cans.

It is also an object to provide a canning machine with an endless conveyer formed of a plurality of moving parts to convey the material to a chute where the material is automatically separated before entering the cans.

It is a further object to provide a canning machine with a plurality of containers which automatically deposit other ingredients into the cans before and after the material carried in the trough.

It is a further object to provide means for delivering cans automatically and place them in position under the delivery chute by the same automatic connections together with automatic device for removing the can after the filling operation.

In the drawings accompanying this specification and forming therewith the application for Letters Patent: Figure 1 is a side elevation of the canning machine showing the supporting frame and driving connections. Fig. 2 is a plan view of the same. Fig. 3 is a front elevation. Fig. 4 is a vertical section on the line 4—4 of Fig. 1, viewed in the direction indicated by the arrows. Fig. 5 is a detail view showing the knife in its inoperative position. Fig. 6 is a view showing the knife just after the severing of a section of the compressed material. Fig. 7 is a detail elevation of the intermittent movement conveyed to the can receiving wheel and the other intermittently operated mechanisms. Fig. 8 is a detail section of the adjustable measuring valve. Fig. 9 is a section on the line 9—9 of Fig. 8.

More specifically in the drawings, 10 designates a base on which is secured the supporting frame work 11 and the legs 12 of the table 14, and plurality of bearing blocks to support the terminal ends of the plurality of vertically disposed shafts connected to the machine.

The main shaft 15 is provided with a driving wheel 16 which preferably extends beyond one side of the main frame, the shaft being extended in the journal block 17 placed near the central line of the machine, where it is provided with the gear wheel 18 which meshes with the gear 19 mounted on the shaft 20 placed parallel with the shaft 15. This shorter shaft is provided with beveled gear 21 which meshes with the gear 22 connected with the vertical shaft 23, which extends upwardly to the lower face of the table 14 where it is suitably journaled. Mounted directly above the bevel gear 22 is a belt pulley 24 over which is carried the belt 25 engaging with a belt pulley 26 mounted on the knife shaft 27, this shaft having suitable bearings in a journal 28 secured to the base and projecting through the journal 29 in the table to a point above the table where is secured the knife 30. Mounted on the shaft 23 above the belt pulley 24 is the sleeve 32 provided with the arm 33 which carries the roller 34 mounted on its outer end which engages with the Geneva wheel 36 which is mounted on the vertical shaft 37. This short shaft carries on its upper end the beveled gear 38 which meshes with the beveled gear 39 mounted on the inner end of a horizontally disposed shaft 40 which is carried to the oppositely disposed side of the frame and provided with the pulley wheels 41 and 42, over which are carried the belts 43 and 44 respectively, over the belt wheels 45 and 46, each one of these pulley wheels being in turn secured to shafts 47 and 48 horizontally disposed and mounted above the shaft 40. Returning to the shaft 23 mounted above the sleeve 32 is a second sleeve 50 provided with the arm 51 on a stud projecting vertically from which is the roller 52 which engages with the slots cut in the Geneva wheel 53 which is mounted on the vertical shaft 54 which is provided with suitable thrust bearings secured to the base, its upper end being carried through a journal 55 in the table 14, and on its upper end above the table is secured the perforated wheel 56 which revolves intermittently immediately under the knife 30. Also secured to the shaft 54 above the Geneva wheel 53, is a gear 57, which meshes with gear 58 mounted on the shaft 60, which is vertically disposed in relation to the machine, and is suitably journaled in the table 14, above which table is keyed the

serrated wheel 61, which receives and delivers the cans according to the intermittent movement given the shaft by the Geneva movement 53.

5 Adjacent the drive pulley 16 on the shaft 15 is mounted the belt wheel 62, over which is carried the belt 63 to the belt pulley 64 mounted on the shaft 65 which is horizontally disposed just below the table in suitable journals and is provided with the pulley wheels 66 and 67 on its outer ends, which are connected by suitable belts to the pulleys 68 and 69 respectively, which are mounted on the outer ends of individual short shafts 10 and 71 which are carried horizontally through the delivering spouts 73 and 74 of the containers 75 and 76 mounted over the table. Inside of the spout 73 is mounted the conical valve 77 which is connected to the shaft 70, suitable bearings in the spout being provided which transversely cross the path of the material to be delivered through the spout, the valve 77 being provided with a recess 78 which forms a measuring chamber in the operation of the apparatus. A cylindrical valve is shown as mounted in the spout 74, which is also provided with the measuring recess 78, the type of material to be measured in these containers regulating to an extent the preferred type of revolving valve used. The table 14 over which these containers 75 and 76 are mounted, is provided with a can receiving chute 80, and a delivery chute 81, a finger 82 mounted on the shaft 65 kicking the can from its engagement with the serrated wheel 61 to the chute 81. Returning to the shaft 48, horizontally disposed above the table 15 provided with journals in the main frame 11, 15 is provided with beveled gears 83 and 84 which in turn meshes with gears 85 and 86 mounted on the lower ends of the vertically disposed shafts 87 and 88, these shafts having the band wheels 89 and 90 respectively, 20 over which are carried the belts 91 and 92 which connect with similar band pulleys 93 and 94 mounted on the vertically disposed shafts 95 and 96, in the same vertical plane as the shafts 87 and 88, these belts being carried in a vertical plane by the movement of their connections to the main drive shaft, their inner adjoining faces being brought parallel to form the vertical walls of a trough formed by these two belts, and a 25 belt 97 with which they engage and which forms a bottom for the trough. This belt 97 is carried over a pulley 98 mounted on the shaft 48 intermediate of the beveled gears, the oppositely disposed end of the endless belt being carried over a pulley 99 mounted in the horizontally disposed shaft 100. The shafts 100, 95 and 96 are each mounted in journal blocks which are slidably mounted in suitable guideways and provided with adjusting screws 101, 102, and 103, by which

the tension on the belts 91, 92 and 97 may be respectively adjusted. The trough formed by these three moving belts progresses in a direction toward the front of the machine, or toward the shaft 48 and opposite the vertical plane carried through the shaft 48 and in line with the axial plane of the shafts 87 and 88, the sharp knife edges of the curved sides of the chute 104 engage with the two vertical surfaces of the belts 92 and 91. The inner wall of the chute beginning at its tangential or vertically disposed portion 105, engages the belt 97 at the point 106, or in a plane horizontally carried through the shaft 48, the front outer wall 107 of the chute being carried from its vertical parallel portion to the wall 105 parallel up over the belt 97 in an arc struck from the axis 48 to a suitable point shown as vertically disposed over the axis. This chute is preferably narrower from front to rear than from side to side, and its rectangular portion terminates at its engagement with the peripheral flanges of the compressing rolls 108 and 109. Below this point the material is compressed into cylindrical form by the annular grooves cut in the periphery of the compressing rolls intermediate of their flanges, the side walls of the chute extending down beyond the axis supporting these compressing rolls, roll 109 being mounted upon the shaft 47 driven intermittently by the belt 43, this shaft being geared by suitable direct gears 111 to gear 110 mounted on the shaft 112 on which the wheel 108 is keyed.

The material receiving wheel 56 is provided with a plurality of cylindrical bores vertically disposed therein, which are of slightly larger diameter than the material as it is compressed by the compressing roll, is intermittently actuated under the delivering portion of the chute 114, where the knives sever the material, as soon as the required amount is obtained or the bore filled. The wheel is now revolved until the material is under the plunger 115 mounted on the vertically disposed plunger rod 116 which is surrounded by spring 117 to normally lift the plunger out of the path of the wheel 56. To properly depress this plunger against the action of the spring, an arm 118 engages with the free end of the rod, this arm forming one arm of the bell crank lever pivoted on the pin 119, the lower arm 120 projecting into the path of a cam 121 mounted on the shaft 122 which is driven by means of the gear wheel 123 meshing with the gear wheel 124 secured on the shaft 65.

The operation of the machine will be readily understood from the drawings and the description, power being provided to drive the main shaft 15, the belts 91, 92, and 97 are intermittently advanced, the ma-

terial to be canned being placed by hand or suitable hoppers not shown, in the trough, the belts being preferably of considerably greater length than shown diagrammatically in the drawings, so that the weight of the contained material will form sufficient friction with the walls, which may be supported by suitable guide rollers not shown, to carry the material down the chute 104 where it meets the compressing rollers which are also intermittently moved coincidently with the movement of the belts. A section of the compressed material is projected into one of the bores in the horizontally disposed wheel 56 when the knife blade which is continuously revolved and is provided with the cutting edge 125 cuts off the required amount, the knife being cut away so that the intermittent movement of the wheel 56 will permit its next succeeding bore registering with the notch 126. From this point the wheel 56 is revolved in the direction indicated by the arrows to a point under the plunger 115, the movement being so timed that a can received from the chute 80 is carried by the serrations in the wheel 61 under the spout 73 where a predetermined amount of sauce and condiments is deposited in the can. The can now moves to register 30 with a bore carrying the compressed material when the plunger is depressed to force the material into the can, which is preferably of slightly greater internal diameter than the diameter of the bores in the wheel 35 56. As the can is carried past the spout 74, oil or suitable dressing or dried condiments are deposited as desired, when the further revolution of the cam wheel 61 moves the can to a point opposite the chute 81 where 40 it is kicked out by the finger 82 into the chute to be carried by any suitable means, not shown, to the can covering operation.

This canning machine is especially adapted for canning fish, and the traveling trough 45 may be formed of belts of sheet metal or webbing, or the chute may be formed with sectional side walls and a continuous flexible bottom which will be engaged by the delivery chute 104 in the same manner without departing from the spirit of the invention.

What I claim is:

1. A canning machine, comprising a frame, a movable trough mounted thereon, a chute 55 engaging with said trough, a plurality of cooperating compressing rolls mounted in registration with said chute and means to receive compressed material from said rolls.

2. A canning machine, comprising a frame, 60 a trough mounted thereon formed of moving members, a curved chute engaging with the sides and bottom of said trough, compressing rolls registering with said chute, means to sever the material below said rolls, 35 and means to receive the severed material.

3. A canning machine, comprising a frame, a trough mounted thereon formed of moving members, a curved chute engaging with the sides and bottom of said trough, compressing rolls adjacent said chute and arranged to receive material therefrom, means to move the members forming said trough, a knife, means to move said knife cooperatively with said trough, and means to contain the material severed by said knife. 70 75

4. A canning machine, comprising a frame, a trough mounted thereon having traveling sides and bottom, a curved chute engaging with the traveling sides and bottom of said trough, compressing rolls arranged to receive material carried in said chute, means to move the traveling sides and bottom of said trough, a knife, means to move said rolls coincidently with said trough, and an apertured receiving wheel arranged to receive material conveyed through said trough and chute and severed by said knife. 80 85

5. A canning machine, comprising a frame, a trough mounted thereon having traveling sides and bottom, a curved chute engaging with the sides and bottom of said trough, compressing rolls in the path of travel of material carried by said chute, means to move the traveling sides and bottom of said trough, a knife, means to move 90 95 said knife co-incidently with said trough, a receiving wheel adapted to receive material cut by said knife, means to revolve said wheel cooperatively, and means to remove said material from said wheel to cans arranged to register therewith. 100

6. A canning machine, comprising a frame, a movable trough mounted thereon, a chute having edges engaging with the sides and bottom of said trough, compressing rolls in the path of said chute, means to move said trough, a knife, means to move said knife coincidently with said trough, a receiving wheel adapted to receive material cut by said knife, means to revolve said 105 110 wheel cooperatively, means to remove said material, and mechanism to place a can in the path of said removing means.

7. A canning machine, comprising a frame, a movable trough mounted thereon, a curved chute engaging with the sides and bottom of said trough, a knife, means to move said knife coincidently with said trough, a receiving wheel adapted to receive material cut by said knife, means to revolve 115 120 said wheel cooperatively, a plunger operating cooperatively with said receiving wheel, a can moving wheel operating coincidently with said receiving wheel, and means to operate said plunger, whereby material is forced from said wheel to a can placed in the path of said plunger. 125

8. A canning machine, comprising a frame, a movable trough mounted thereon, a curved chute engaging with the sides and 130

4

bottom of said trough, a knife, means to move said knife coincidently with said trough, a receiving wheel adapted to receive material cut by said knife, means to revolve 5 said wheel coöperatively, a plunger operating coöperatively with said receiving wheel, a can moving wheel operating coincidently with said receiving wheel, means to operate said plunger, and means connected to said 10 plunger operating means to kick the filled cans from engagement with said moving can wheel.

9. A canning machine, comprising a frame, a movable trough mounted thereon, a 15 curved chute engaging with the sides and bottom of said trough, a knife, means to move said knife coincidently with said trough, a receiving wheel adapted to receive material cut by said knife, means to revolve 20 said wheel coöperatively, a plunger operating coöperatively with said receiving wheel, a can moving wheel operating coincidently with said receiving wheel, means to operate said plunger, a plurality of containers placed 25 in the path of cans carried by said can moving wheel, and means operated by said plunger operating means to deliver material to said cans.

10. A canning machine, comprising a 30 frame, a movable trough mounted thereon, a curved chute engaging with the sides and bottom of said trough, a knife, means to move said knife coincidently with said trough, a receiving wheel adapted to receive 35 material cut by said knife, means to revolve said wheel coöperatively, a plunger operating coöperatively with said receiving wheel, a can moving wheel operating coincidently with said receiving wheel, means to 40 operate said plunger, a plurality of containers placed in the path of cans carried by said can moving wheel, revolving valves mounted in said containers provided with measuring recesses, means to revolve said 45 valves in coincidence with said can wheel.

11. A canning machine, comprising a frame, a delivery trough mounted thereon in a substantially horizontal position, a ver-

tical chute having a curved portion adapted to engage with the sides and bottom of said trough, a pair of coöperating pressure rolls revolubly mounted in said chute below said curved portion and adapted to convert material passing through said chute from a rectangular cross section to a circular cross 55 section, a severing knife mounted below said chute, a wheel having a plurality of cylindrical openings therein adapted to register below said rolls and receive material passed therethrough, a plunger means mounted adjacent said receiving wheel and adapted to remove the material therefrom, and a wheel arranged to pass empty cans into the path of travel of said plunger, and means to operate said rolls, knife, receiving wheel and 60 can wheel coöperatively.

12. A canning machine, comprising a frame, a trough horizontally mounted thereon formed of endless belts to provide a bottom and sides therefor, a vertically disposed chute having a curved upper portion with sharpened edges to engage the bottom and sides of said trough formed by the moving belts, a pair of coöperating pressure rolls revolubly mounted in said chute below said curved portion and adapted to convert material passing through said chute from a rectangular cross section to a circular cross section, a severing knife mounted below said chute, a wheel having a plurality of cylindrical openings therein adapted to register below said rolls and receive material passed therethrough, a plunger means mounted adjacent said receiving wheel and adapted to remove the material therefrom, and a wheel arranged to pass empty cans into the path of travel of said plunger, and means to operate said rolls, knife, receiving wheel and can wheel coöperatively.

In witness that I claim the foregoing I have hereunto subscribed my name this 4th day of March, 1913.

CLARENCE L. BENTLEY.
